MANICURE IMPLEMENT

Donald R. Adams, P.O. Box 865,
Felton, Calif. 95018

Filed July 19, 1966, Ser. No. 3,126

Term of patent 14 years

(Cl. D86—10)

FIGURE 1 is a top perspective view of a manicure implement showing a first embodiment of my new design, the handle portion having a pair of elongated parallel bosses that are rounded in horizontal and vertical plane;

FIGURE 2 is a side elevational view of the design of FIGURE 1;

FIGURE 3 is a bottom plan view thereof;

FIGURE 4 is an end elevational view taken from the right of FIGURE 1;

FIGURE 5 is an end elevational view taken from the left of FIGURE 1;

FIGURE 6 is a top perspective view of a second embodiment of the design shown in FIGURE 1, the handle portion having a pair of elongated parallel bosses that are substantially flat in horizontal and vertical plane, the manicure implement is shown broken away for convenience of illustration; and

FIGURE 7 is an end elevational view taken from the right of FIGURE 6.

The characteristic features of my design reside in the combination on an elongated manicure implement rounded at the base in both horizontal and vertical planes of an abrasive center section, a pointed end and a handle end, the handle end having a pair of elongated parallel bosses all as shown.

I claim:

The ornamental design for a manicure implement, substantially as shown and described.
